SAFE AND LINER THEREFOR

Andrew M. De Voursney, Milwaukee, Wis.

Application May 7, 1936, Serial No. 78,308

14 Claims.

(Cl. 109—1)

This invention relates to an improvement in safes and liners therefor.

It is the object of the invention to improve a safe of the "Corliss" type by means discouraging unauthorized entry, first by rendering such entry more difficult, and secondly by depriving the burglar of the fruit of his labor.

The country contains many thousand safes of the Corliss type which are regarded by many persons as obsolete for the reason that improvements in the technique of thermal cutting has made it possible for safe burglars to penetrate the walls with a torch and remove the contents. The doors of this type of safe are still regarded as virtually impregnable either by blowing, drilling, or thermal cutting.

The practice of the safe burglar is as follows: With the extremely hot flame of a torch such as is commercially used either for cutting or welding, the thief removes the metal wall of the safe until he penetrates the interior. During this operation the wall of the safe has become highly heated, and the lack of sufficient oxygen in the interior is frequently all that keeps the contents from being burned. As soon as the flame penetrates the wall the thief immediately introduces a quantity of water to submerge the contents and thereby prevent them from burning during his subsequent cutting operations to enlarge the hole.

The present invention seeks to improve both existing and future safes of this type by providing a liner which is made sectionally for installation in existing equipment and which is not merely made of metal highly resistant to thermal cutting so that intense heat is required for its penetration, but in which additionally I provide an excess of oxygen made available whenever the temperature becomes excessive to assure the destruction of the combustible contents of the safe. Even though the contents are not wholly destroyed, they will be rendered non-negotiable, and even if they are wholly destroyed in the ordinarily accepted sense they can still be identified and redeemed due to improved ultra violet means of ascertaining the original writing. Thus, there is no loss either to the bank or the insurer of the bank, but the burglar is precluded from profiting and therefore his incentive is destroyed.

Other objects will appear more specifically from the following disclosure.

In the drawing

Figure 1 is a view in axial section of a safe embodying my invention.

Figure 2 is a view taken in section in the plane indicated at 2—2 in Figure 1.

Figure 3 is a fragmentary detail view on an enlarged scale showing the various layers which must be penetrated by the burglar to gain access to my improved safe.

Like parts are identified by the same reference characters throughout the several views.

In the drawing I have shown at 4 the door, and at 5 the wall of a conventional safe. In accordance with this invention I have assembled within the safe the parts of a pre-fabricated interior jacket or liner generically designated by reference character 6, which protects all portions of the wall 5 and is provided with an opening at 7 registering with the opening which is closed by the door 4.

In practice the liner is made up in at least five sector-like parts 8, 9, 10, 11 and 12, provided with registering lugs 15 bolted together by the bolts 16. The use of five sectors is required in order to permit each sector to be introduced into the door opening of existing safes.

Each of the sectors 8, 9, 10, 11 and 12 is preferably two ply. The inner ply 17 is made of tungsten steel, which burns at an extremely high temperature and requires a special tip on the torch used for cutting it. Whereas the safe wall 5 has heretofore been made of manganese steel (to resist drilling) and will flow at about 2200° F., the inner 30 ply of the liner, if made of tungsten steel, will not flow until the temperature reaches or exceeds 5300° F.

The outer ply 18, while not essential to the invention, is preferred because it may be made of a copper base burn-resisting metal having a heat conductivity so great as to distribute the heat throughout the liner and the interior of the safe before the point of application of the flame can be raised to a temperature sufficient for cutting. Any metal of high heat conductivity can be used for the ply 18 but, as above indicated, copper base alloys are usual where heat conductivity is desired.

The liner may be left entirely loose within the safe wall if desired, but I prefer to fill the space between the liner and the safe wall with a layer 19 of concrete with which nails have been liberally interspersed, as indicated in Fig. 3 to resist drilling. The concrete is not only proof against attack by a torch, but it also acts to some extent as a thermal insulator to confine within the safe and the interior thereof all the heat developed during attempts to penetrate the liner by cutting.

Obviously, the construction disclosed will great-

ly increase the mere mechanical difficulty of penetration. Using a low temperature tip, the burglar will speedily cut with his torch the outer wall 5, but he will then be confronted with a concrete 10 filler in which interspersed nails make drilling difficult, so that his only means of penetrating this layer will involve chipping away the concrete with a chisel or the like. This will be rendered difficult not merely by the nails, but by the fact 15 that the location of the concrete filler on the inside rather than the outside of the safe wall will require the thief to operate through the relatively small opening which he has been able to burn in the exterior wall. Since criminals are notoriously 20 lazy, and are also obliged to work against time, the concrete layer in this location will offer a severe handicap.

When the criminal has penetrated the concrete the tungsten steel will offer a very substantial obstacle 25 requiring the highest temperature for its penetration, and the copper base burn-resisting ply 18, if used, will tend to carry away the heat with such rapidity as to prevent the operator from raising the temperature to the point where he can cut the inner ply 17. The outer ply 18, incidentally, may be held to the inner ply 17, by cap screws 20 threaded into blind holes as shown in Fig. 2.

From the foregoing it will be apparent that the difficulty of access is greatly increased not merely by the materials used and the number of different plies or layers employed, but by the particular order in which such plies or layers are incorporated in my improved safe structure.

Assuming that the would-be burglar succeeds in penetrating the safe and its liner, it is apparent that the interior temperature will be much higher than anything with which the burglar has heretofore been obliged to contend. Not only has he found it necessary to use a temperature of 5300° F. to cut the inner liner ply of tungsten steel, but the outer liner ply of copper base metal has distributed the heat throughout the liner and the interior of the safe, its outward flow being resisted by the concrete filler (or the air space between the liner and the safe wall if no filler is used). In consequence of the extremely high temperature which will exist throughout the interior of the safe, all combustible contents will surely be destroyed or rendered non-negotiable if sufficient oxygen is present.

To assure such destruction or mutilation, I prefer to suspend by means of the carrier 23 from one of the bolts 16, a vessel 24 containing a closure 25 adapted to hold in such vessel a supply of oxygen under pressure. Obviously oxygenating compounds may be used. In this particular embodiment of the invention, however, I use free oxygen gas, and either the container 24 or its closure 25, or both, are made of metal such as lead or white metal which fuses at a low temperature not to exceed a few hundred degrees F. Thus, any effort to cut thermally the liner 6 will result in immediate release within the liner of a sufficient quantity of oxygen to assure the combustion of negotiable instruments and currency contained in the safe. It is to be noted that this will occur before any opening can be made through which water could be introduced and consequently the burglar will find, upon entry, that the securities within the safe are all non-negotiable.

I also employ, as a means of assuring the destruction of the contents of the safe, a material which will be ignited by the torch used in penetrat-

trating the safe and which will be self-oxygenating to burn at an exceedingly high temperature. Such a material is the well known "Thermite" which, in powdered form, as at 26, may be suspended in shallow pans 27 of any light sheet metal or other material comprising supplemental liners for the individual lining sectors. Such pans are shown applied to the end wall surfaces and top wall surfaces of sectors 8 and 12 in Figs. 1 and 2.

As above indicated, even badly charred securities and currency can be identified sufficiently for replacement purposes or redemption by using photographic processes and other technical improvements such as those including the use of ultra violet light. Even if the contents of the safe were wholly destroyed beyond redemption or replacement, however, the invention would still serve its purpose in depriving the burglar of any profit and thus tending to discourage future effort.

I claim:

1. The combination with a metal safe wall, of a liner comprising two plies disposed within said wall, one of said plies being more thermally resistant than the wall and the other of said plies being highly heat conductive, the latter ply being interposed between the former ply and the wall, whereby to dissipate the heat of a torch and to raise the temperature of a safe containing such wall before such torch can gain access to the thermally resistant ply.

2. In a safe, the combination with a metallic wall, of a liner substantially co-extensive with the wall and comprising a metal more thermally resistant than the wall, and a cementitious filler between the liner and the wall, said filler being substantially impregnable to attack by heat and yieldable only to mechanical assault whereby to limit the area of access to the thermally resistant ply.

3. In a safe, the combination with a wall, of a liner substantially co-extensive with the wall and comprising an inner ply more heat resistant than the wall, an intermediate ply having a higher heat conductivity than the inner ply of the wall, and a non-metallic incombustible filler between said intermediate ply and the wall.

4. The combination with a safe having a manganese steel wall and a door, of a liner substantially co-extensive with the wall and comprising an inner ply of tungsten steel, an intermediate copper base heat conducting ply, and a concrete filler between the intermediate ply and the wall.

5. The combination with a safe having a wall provided with a door opening and a door, of a liner comprising peripheral sections and end sections applicable about the interior of the wall and provided with means for connecting the safe sections together to comprise a complete lining substantially co-extensive with said wall, each such section being receivable through the door opening.

6. The combination with a safe having a wall provided with a door opening and a door, of a liner comprising peripheral sections and end sections applicable about the interior of the wall and provided with means for connecting the safe sections together to comprise a complete lining substantially co-extensive with said wall, each such section being receivable through the door opening and including a plurality of plies, one of which is more highly heat resistant than the wall, and the other of which is more highly heat conductive than the wall.

7. The combination with a safe, of a container

- within the safe providing a supply of oxygen, and thermally responsive means operable in the presence of excessive heat to release the oxygen from the container.
5. 8. The combination with a safe, of a vessel within the safe containing oxygen under pressure and including thermally responsive means for releasing said oxygen when the temperature within the safe becomes excessive.
10. 9. The combination with a safe, of a vessel having a low temperature fusible portion, said vessel containing oxygen and being disposed within the safe.
10. 10. The combination with a safe having a wall, 15 of a liner substantially co-extensive with said wall and comprising metal more resistant to torch burning than said wall, and an oxygen containing vessel within said liner having thermally responsive means for releasing its contents at temperatures less than those which will be produced within the liner by any attempt to penetrate the liner thermally.
11. The combination with a safe having a wall and a liner for said wall, of a receptacle having 20 at least a fusible portion disposed within said
- liner, said portion being adapted to release the contents of the receptacle at temperatures below those which will be occasioned within the liner in the thermal penetration of the safe.
12. The combination with a safe, of thermally 5 responsive means for supplying oxygen to the interior thereof.
13. The combination with a safe, of means therewithin for destroying the contents of the safe upon thermal attack, said means comprising 10 a gaseous medium adapted in the presence of heat to destroy the contents of the safe, a vessel containing said medium, and thermally responsive means for releasing said medium in the presence of excessive heat.
14. The combination with a safe, of means therewithin for destroying the contents of the safe upon thermal attack, said means comprising 15 an internal liner having high thermal resistance, whereby it can be penetrated only by excessive heat, and thermal responsive means operative in the presence of excessive heat for delivering an oxygenating medium to the interior of the liner.
